PORTABLE DESK LAMP

Laurence E. Corcoran, Buffalo, N. Y.

Application October 13, 1949, Serial No. 121,211

3 Claims. (Cl. 240—81)

1

This invention relates to improvements in portable desk or table lamps of the type which includes a pedestal comprising a base and an upright column formed and proportioned to serve as a hand grip when the lamp is to be moved from one position to another, a lower cup-like reflector directed upwardly, enclosing the lamp bulb and having its lower portion adjoining the column and formed as a cap to enclose the lamp socket, and a cover which provides, or carries, an upper reflector directed downwardly, the cover being supported from the lower reflector.

In lamps of this type the base, column and cup (with the upper reflector) are formed as separate elements and their assembly is maintained by a tubular threaded stem which projects through the pedestal and is connected to the lamp socket, the stem serving as a conduit for the wires and, in maintaining the assembly of the parts, cooperating with the cup and the base as clamping elements in relation to the column.

Such lamps are advantageous because they give a concentrated pool of light upon the working plane at an angle such as to minimize glare and also conceal the source of light from the worker at the desk or table. In the use of such lamps it is frequently desirable that they be moved from one position to another on the desk or table and it is for the purpose of convenience in effecting such movement that the column is formed and proportioned to serve as a hand grip. However, as heretofore constructed, such lamps have had a serious disadvantage in that the reflector becomes highly heated by the radiation from the lamp bulb and its heat is transmitted by conduction to the column with the result that after a few minutes of use the column becomes so hot that it is not practical to grasp it in order to move the lamp, wherefore the lamp is quite apt to be dropped when the heated column is grasped as a hand grip. Therefore, in order conveniently to move the lamp it is necessary to switch off the light and allow sufficient time for the column to cool to a point at which it can be conveniently grasped.

The object of the invention is to provide simple and practical means of novel character, included in the assembly of the pedestal (base and column) and the cup, for so minimizing the conduction of heat to the column as, in effect, substantially prevent such conduction, whereby the column may at any time be comfortably grasped with the bulb lighted and the lamp may be readily moved to any desired location on the desk or table or to another desk or table.

2

In the accompanying drawing:

Figure 1 is an elevation of a lamp in accordance with the invention.

Figure 2 is a vertical sectional view of the base, column, cup and lower reflector features of the lamp, the electric bulb being shown in elevation.

Figure 3 is an exploded perspective view of elements employed in the heat insulation of the column from the cup.

The known elements of the lamp, in relation to the features which constitutes the invention, include the base 1, the tubular column 2, the lower upwardly facing conical reflector 3 and the tubular cup 4, preferably integral with the reflector and projecting axially from its lower end, the cup 4 being preferably of the same diameter as the column and being provided with a base 5 having a central opening to accommodate the threaded tubular stem 6 which serves as a conduit for the wires and by which the assembly of the enumerated parts is maintained. The reflecting surface, in accordance with known practice, may be provided directly on the reflector 3 or it may, as shown and preferred, be provided by a separate cup shaped element 7 which is fitted within the reflector and has a bottom opening through which the neck of the lamp bulb may be inserted, the lamp bulb projecting from the usual socket 8 enclosed within the cup 4. The cup 4 has at one side an opening to accommodate the stem of the usual lamp switch 9.

The lamp, pursuant to known mechanical design, is completed by a downwardly facing cover 10 supported from the reflector 3. The cover 10 includes a downwardly facing reflector feature and has its lower edge below the upper edge of the reflector 3, thereby to conceal the source of light from the worker and to protect the worker from the glare of the direct rays of light. While the cover 10 may be finished to serve as a reflector it is preferable that the reflector feature be provided by an appropriately formed reflector plate 11 which is sufficiently shown by dotted lines in Figure 1. The cover carries the usual ornamental finial 12.

The cover, in accordance with known practice, is supported from the reflector 3 by suitably formed upwardly projecting arms 13, the lower portions of which may be bolted or otherwise secured to the upper portion of the reflector 3 and the upper portions of which directly support the cover. In the construction shown wherein the cover 10 is connected to a separate reflector plate 11 the upper portions of the arms

13 are formed with inward angular extensions 14 which may be connected in any suitable manner, i. e. by screws or rivets, to the marginal portion of the plate 11.

In the construction shown wherein the separate reflector plate 11 is provided, the finial 12 has a threaded stem 15 which serves to connect the cover and the reflector plate and to cause the edge portion of the reflector plate to bear securely against the cover.

In accordance with the invention the tubular column 2 is closed at its upper end by a washer 16 of inverted cup shape, that is to say, a washer which is provided with an upwardly directed cylindrical flange 17 overlying and slightly spaced from the lower end of the cup 4. The column 2 is also closed at its lower end and the end closures provide a dead air space 18 within the column. While the lower end of the column 2 could be closed by bearing directly upon the upper face of the base 1, it is preferable that it bear upon a washer 19 which in turn bears upon the upper face of the base 1. The washer 19 may be flat or it may, as shown, be cup-shaped, that is to say formed similarly to the washer 16 but with its cylindrical flange 20 extending downwardly and bearing upon the upper face of the base 2. The washers 16 and 19 are formed with central openings and the stem 6 extends loosely through these openings. The washer 16 is preferably formed with a downwardly projecting boss 22 and the washer 19 is preferably formed with a similar, but upwardly projecting, boss 23. The diameters of the bosses 22 and 23 conform to the internal diameter of the column 2 whereby these bosses have a close fit within the adjacent ends of the column and serve two functions, one of which is positively to maintain the centered alignment of the column with respect to the base 1 and the cup 4 and the other of which is substantially to seal the dead air space 18.

The washer 16 is heat insulated from the cup 4 by piled washers 24 of suitable heat insulating material, e. g., compressed asbestos felt, the upper face of the upper washer 24 bearing against the underface of the base 5 of the cup 4 and the lower face of the lower washer 24 bearing against the upper face of the washer 16. The cupped form of the washer 16 provides a closed chamber 25 in which the washers 24 are arranged. It will, of course, be obvious that a single heat insulating washer of suitable thickness may be used instead of, and in the same relation and for the same purpose as, the separate piled washers 24.

The slight spacing of the flange 17 of the washer 16 from the lower end of the cup 4 substantially prevents the transmission of heat by conduction from the cup 4 to the flange 17. The washers 24 prevent the transmission of heat by conduction from the cup 4 to the washer 16 and the column 2. Any heat that may be transmitted by conduction from the cup 4 to the stem 6 is substantially occluded from the column 2 by the dead air space 18 and from the washers 16 and 19 by virtue of their loose fit about the stem 6. By virtue of these several heat insulating features the column 2 at all times remains comfortably cool, that is to say, substantially at room temperature whereby it may be comfortably

grasped when the lamp is to be moved from one position to another. The washer 16 has the further advantage of visually demarking the column 2 from the cup 4 whereby the user of the lamp will naturally grasp the column 2 as a hand grip and will not grasp the cup 4.

I claim:

1. A portable desk lamp of the type which includes a pedestal comprising a base and an upright tubular column formed and proportioned to serve as a hand grip when the lamp is to be moved from one position to another, a lower cup-like reflector directed upwardly, enclosing the lamp bulb with its lower portion adjoining the column and formed as a cup to enclose the lamp socket, the cup having a base, the column being positioned between the bases of the cup and the pedestal, the bases of the cup and the pedestal being provided with alining central openings, and a stem externally threaded and extending through the column and the central openings in the bases of the cup and of the pedestal and cooperating with the bases of the cup and pedestal as clamping elements in relation to the column; wherein the opposite ends of the column, adjoining the bases of the cup and the pedestal respectively are closed to provide a dead air space, the closure at the upper end of the column consisting of a cup-shaped washer which abuts the upper end of the column, has a central opening through which the stem extends loosely and also has an upwardly projecting cylindrical flange which surrounds and is spaced from the lower end of the cup, and additional washer means of heat insulating material is interposed between the cup-shaped washer and the base of the cup.

2. A portable desk lamp as set forth in claim 1 wherein the closures for the opposite ends of the column which form the dead air space are formed with bosses which project into the adjacent ends of the column and snugly fit into the cylindrical wall thereof, thereby to maintain the central alignment of the column with respect to the bases of the pedestal and the cup and substantially to seal the dead air space.

3. A portable desk lamp as set forth in claim 1 wherein the closure at the lower end of the column consists of a washer bearing against the upper face of the base of the pedestal and each of the closure washers is provided with a boss which projects into the adjacent end of the column and snugly fits into a cylindrical wall thereof, thereby to maintain the central alignment of the column with respect to the base of the pedestal and the cup and substantially seal the dead air space.

LAURENCE E. CORCORAN.
